US0D1082875S

(12) **United States Design Patent** (10) **Patent No.:** **US D1,082,875 S**
(45) **Date of Patent:** **** Jul. 8, 2025**

(54) **KINK PREVENTING DEVICE**

(71) Applicant: **Kobe Steel, Ltd.**, Kobe (JP)
(72) Inventors: **Ryota Shimozawa**, Fujisawa (JP);
Satoshi Ujino, Fujisawa (JP); **Koji Sato**, Fujisawa (JP)
(73) Assignee: **Kobe Steel, Ltd.**, Kobe (JP)
(**) Term: **15 Years**
(21) Appl. No.: **29/772,964**
(22) Filed: **Mar. 5, 2021**

(30) **Foreign Application Priority Data**

(57) **CLAIM**

The ornamental design for a kink preventing device as shown and described.

DESCRIPTION

FIG. 1 is a perspective view of a kink preventing device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged perspective view thereof.

The broken lines depict portions of the kink preventing device in which the design is embodied that are not considered part of the claimed design.

1 Claim, 5 Drawing Sheets
